James M. Shirley
ATTORNEY

UNITED STATES PATENT OFFICE

PAULINE GRAYSON, OF NEW YORK, N. Y.

CLEANING DEVICE

Application filed September 24, 1927. Serial No. 221,652.

My invention relates to cleaning devices for household use.

The object of my invention is to provide a device for this purpose embodying a frame adapted to support a scrub brush and mop, and having means for carrying a cleaning fluid, all arranged for separate or cooperative use, all of said parts being mounted in easily separable relation to each other and to the frame.

10 Referring to the drawings which form a part of this specification,

Fig. 1 is a side view of a device embodying my invention.

15 Fig. 2 is a front view of the lower part of my device shown on a larger scale.

Fig. 3 is a side view, shown partly in section, the mop being shown in its twisted condition.

20 Fig. 4 is a sectional view of the handle portion of the device shown on a larger scale than in Fig. 1.

The frame comprises a stiff iron rod A, bent in triangular form to provide two side portions A'—A', and a lower cross-rod portion A², the ends of which are connected to a light steel tube B by a clasp-ring C, located a short distance above the lower end of the tube B. D indicates a cone-shaped apron, the 25 upper small end of which is also firmly secured to the tube B by brazing or welding, and the side rod portions A' are firmly welded thereto on the inner sides thereof, which construction serves to brace the side rods. A wooden pole E extends from above and thru the tube B and is provided with a snap-hook F at its lower end, the shank of which is rigidly fixed thereon, said shank being indicated by F'.

30 Connected in fixed relation to the lower end and upon the upper side of the frame portion A² is a rectangular shaped support G, made of resilient metal, the upwardly extending side arms of which are provided with holes G', respectively, in which end pins H' on the ends of the drainage receptacle H rest.

35 The side portions G are also provided with notches G² to receive the flat supports I' carried at the ends of the tank I. The tank I

serves to contain the cleaning fluid and is filled thru the capped opening J.

K—K, respectively, indicate hooks carried by the side arms G in fixed relation therewith.

M is a mop consisting of a single piece of 55 fabric, rectangular in form, having its bottom and top ends folded back to bring the eyelets L—L, respectively, located near its side edges, in overlapping relation as shown. These eyelets engage the hooks K—K. The mop serves to hold the side arms from spreading but is sufficiently elastic that it may be stretched to engage the hooks K—K. The eyelets provided on the upper end of the mop engage the snap hook F.

60 The receptacle H is provided with an opening N, rectangular in form, which extends its entire length and is also provided with inclined top walls O—O to guide the fluid wrung from the mop into the drainage receptacle H.

65 The tank I is provided with a tube P, which extends to the bottom of the receptacle and is formed with a gooseneck P' at its upper end opening into a triangular shaped spraying nozzle R having a very restricted outlet at R' which extends the entire width thereof.

A long nipple S is fitted in the top wall of the tank I, into which the lower end of a soft rubber tube T fits in airtight relation and is held therein by friction and is removable therefrom by pulling the end of the tube from the nipple.

70 Connected to the upper end of the tube T is a rubber pump U, having an air inlet check valve U' of the usual construction located in its upper end and supported in position on the tube B by clasp rings V—V, respectively, which are fixed thereto.

75 The pole E is held in any desired position by a rubber disc W, the inner edges of which are slotted radially to clasp the pole in frictional engagement. The disc is held in position by a flanged ring X which is screwed on the top end of the tube B, as shown.

80 The scrub brush Y is held in a spring-wire frame Z, which is carried by the frame portion A². The frame Z is formed to enter the longitudinal grooves of the brush and hold it by a clasping action in easily removable re-

lation by an endwise movement of the brush.

To place the receptacle H in position on the frame, the side arms G are sprung apart from each other a distance sufficient for the pins H' to enter the holes G', after which the arms are permitted to spring back to their vertical position and the eyelets, L—L respectively, are connected with the hooks K—K. The upper end of the mop M is then connected to the snap hook F.

10 The tank I is then placed in position in the frame as shown, after which the end of the soft rubber tube is forced tightly into the nipple S.

15 In using the device, assuming the tank I is filled with water, or other cleaning fluid, and the mop is held in the position shown in Fig. 1, the pump V is pressed to force air into the receptacle I above the surface of the fluid therein to force the fluid therefrom thru the tube P and the spraying nozzle R. By this action the cleaning fluid is sprayed onto the surface to be cleaned in front of the brush, after which the surface may be scrubbed, as

25 will be readily understood.

The mop may then be placed in position for use by sliding the pole E downward thru the tube B to the position shown in dotted lines in Fig. 3, thus bringing the mop onto the surface to be cleaned where it may be used independent of the brush, or in conjunction therewith by permitting the mop to rest under the bristles of the brush against the surface being cleaned. The pole E is then drawn upwardly

35 thru the tube to its extreme upper position and rotated to twist the mop and express the fluid therefrom into the receptacle H, as will be readily understood.

40 This operation may be repeated as often as desired until the supply of cleaning fluid in the tank I is exhausted. The tank I may then be removed from the frame G by lifting it therefrom, after which the fluid may be dumped from the receptacle H without further disassembly, if desired. The tank I may then be refilled and replaced in the frame G and the device is then prepared for further use.

45 Having thus described my invention, I claim as new:

50 1. A cleaning device comprising a frame and a handle, a mop and a drainage receptacle mounted on said frame, and means for expressing fluid from said mop into said receptacle.

55 2. A cleaning device comprising a frame and a handle, a mop, a drainage receptacle mounted on said frame, the lower end of said mop being held adjacent to the top of said drainage receptacle, and means for wringing said mop.

60 3. A cleaning device comprising a frame and a hollow handle, a rotatable pole extending thru said handle at both ends thereof, a mop connected to the lower end of said pole,

a drainage receptacle carried by said frame and means for holding the lower end of the mop adjacent the top of said drainage receptacle.

65 In testimony whereof I have affixed my signature.

PAULINE GRAYSON.
